(57) **CLAIM**

The ornamental design for a therapy device, substantially as shown and described.

DESCRIPTION

FIG. 1 is a top, front, right side perspective view of a therapy device showing my new design;

FIG. 2 is a front elevational view of the therapy device shown in FIG. 1;

FIG. 3 is a left side elevational view of the therapy device shown in FIG. 1;

FIG. 4 is a top plan view of the therapy device shown in FIG. 1;

FIG. 5 is a back elevational view of the therapy device shown in FIG. 1;

FIG. 6 is a right side elevational view of the therapy device shown in FIG. 1;

FIG. 7 is a bottom plan view of the therapy device shown in FIG. 1;

FIG. 8 is a front elevational view of the therapy device shown in FIG. 1 with the tool rotated 120° clockwise to an alternative position;

FIG. 9 is a front elevational view of the therapy device shown in FIG. 1 with the tool rotated 120° counterclockwise to an alternative position; and,

FIG. 10 is a front elevational view of the therapy device shown in FIG. 1 as it might be employed by a user.

The broken line indicating the human figure in FIG. 10 shows environment in the drawing and is for illustrative purposes only and forms no part of the claimed design.

1 Claim, 5 Drawing Sheets
